UNITED STATES PATENT OFFICE

ALEXANDER H. COOKE, OF NEW YORK, N. Y., ASSIGNOR TO THE ATLANTIC COAST FISHERIES COMPANY, OF NEW YORK, N. Y., A CORPORATION OF MAINE

FREEZING APPARATUS

Application filed February 10, 1927. Serial No. 167,068.

This invention relates to a novel and improved apparatus for freezing comestibles, and finds particular utility in the freezing of fish and the like. In the prior art it has been customary to place comestibles in trays, pans or plates and store them in a refrigerator until frozen. This procedure has been expensive in both time and apparatus because of the large number of pans or the like that it has been necessary to buy and also because of the fact that it usually takes about twenty-four hours to effectively freeze the comestibles, even when the pans are placed directly upon refrigerating coils. This length of time is necessary with the usual apparatus because of the fact that the refrigerant flowing through the pipes in a refrigerator contacts only with the interior surface of those pipes and this surface forms the only conducting surface. Even when a pan is placed directly upon the pipes, the contact between each pipe and a pan is practically a point of contact, which sharply limits the conduction of heat from the comestibles in the pan to the refrigerant in the pipe. Moreover, the pans themselves are thin and therefore form poor conductors of heat.

It is the object of my invention to provide a means for freezing comestibles which shall very greatly reduce the time necessary for the freezing to take place and which shall also avoid the necessity of employing containers except for special comestibles, thus cutting down the cost of such containers and the handling of them.

The foregoing object I achieve by providing an endless conveyor having thereon a plurality of carriers, the carriers being disposed above a refrigerant tank and having fins or other projections extending downwardly into the refrigerant in the tank. The refrigerant is kept in circulation in a direction opposed to the direction of movement of the conveyor so that the fins are continually subjected to the action of fresh refrigerant. The fins are made of large cross-section and are provided with large conducting surfaces so that there is provided the combination of a relatively rapid flow of refrigerant together with a large conducting surface to

transmit the heat to the refrigerant and a large cross-sectional area to carry the heat from the comestibles to the conducting surface.

The carriers are preferably in the form of flat plates and are supported on tracks which carry them past suitable stations for loading and unloading. The comestibles may be placed directly on the plates and the refrigeration takes place entirely by the passage of heat from the comestibles through the carrier to the refrigerant. The air surrounding the carriers may also be cooled by suitable coils, but the air itself is not relied upon as a means of freezing the fish rapidly, but is used to maintain a low temperature on the upper surface of the fish, thereby further increasing the rapidity of the freezing.

In order to expedite removal of comestibles at the unloading stations, there is provided a tank containing liquid which may have the same composition as the refrigerant and which is maintained at a temperature above the freezing point of the comestible to be frozen, and into which the fins on the carriers pass as the carriers approach the unloading station.

Further objects and advantages of my invention will be apparent during the following description when taken in connection with the accompanying drawings, in which:

Figure 1 is a diagrammatic plan view of the entire apparatus.

Figure 2 is a similar view on a larger scale of one end of the apparatus, the end at which the loading and unloading stations are disposed.

Figure 2-A is a similar view of the other end of the apparatus than that shown in Figure 2.

Figure 3 is a section on the line 3-3 of Figure 1.

Figure 4 is a cross-sectional view through the cleaning apparatus shown in Figure 3.

Figure 5 is a cross-sectional view on an enlarged scale, this view being taken through the refrigerant tank and approximately on the line 5-5 of Figure 7.

Figure 6 is a detail view showing the ar-

rangement by which the carriers are withdrawn from the cold refrigerant tank.

Figure 7 is a view of the structure shown in Figure 5 as viewed from the left of that figure, parts being broken away.

5 Figure 8 is a profile of the left end of the apparatus, as viewed in Figure 1.

Figure 9 is a plan view of a portion of one of the carriers, parts being broken away.

10 Figure 10 is a view showing how oysters, scallops and the like may be handled on one of the carriers.

Figure 11 is a fragmentary section of a fin showing one way in which it may be roughened.

15 Figure 12 is a similar view showing another form of roughening a fin.

Referring now to the drawings it will be seen that my apparatus comprises an endless conveyor 1, here shown in the form of an endless chain, and this chain is supported by a plurality of hangers 2 carrying rollers 3 running on a track 4. The chain is actuated by suitable sprockets 5 or the like, which are operated from any suitable source of power, not shown.

Disposed substantially parallel to the conveyor and outside of the path taken thereby is a tank which is adapted to contain refrigerant. This tank is designated 6 and extends substantially the entire length of the conveyor, beginning at the point designated 7 in Figures 1 and 2 and ending at the approximate point designated 8 in those figures. Referring still to the same figures, there is shown at 9 a loading station at which may stand an operator in order that he may place comestibles upon the carriers 10 as they pass him. These carriers are secured to the conveyor 1 as by means of links 11 which are pivoted to the brackets 12 on the conveyor and to the brackets 13 on the carriers. This construction is best shown in Figure 7.

15 The carriers are preferably in the form of relatively flat plates, as best shown in Figures 5 and 7, and are supported by the brackets 13 and 14 upon suitable rails 15 and 16, the brackets carrying the rollers which contact with these rails, as best shown in Figure 5. The roller 17 contacting with the rail 15 is flanged, as shown, in order to maintain the roller on the rail, while the roller 18 is in the form of a caster roller so that it may support the carrier without binding on the curves of the track. Each carrier is provided with a plurality of depending fins 19 which extend downwardly into the refrigerant 20 in the tank 6. These fins are shown in Figure 9 as being stepped whereby, when the fins are moved through the refrigerant, eddy currents will be formed and thus prevent the formation of any film of warm refrigerant close to the surface of the fins. The refrigerant will be agitated by the projections or steps on the fins, thus causing the currents referred to

above and preventing the formation of the objectionable film of warm refrigerant. The surfaces of the fins will thus be continuously exposed to fresh cold refrigerant.

70 The conveyor will move the carriers through the refrigerant and the track formed by the rails 15 and 16 will support the carriers so that the top thereof will always remain out of contact with the refrigerant. In fact the carrier extends substantially across the tank as shown in Figure 5 and thus obviates the danger of refrigerant coming in contact with the top surface of the carrier, where the comestibles are placed. The top of the carrier is extended outwardly in the form of a flange 21 which supports the brackets 14. This flange is continuous, so as to form an apron on which comestibles may be moved when being placed on or removed from a carrier.

80 As the carriers leave the cold refrigerant tank at 8 they are elevated due to the inclination of the track, as indicated at 22 in Figure 6, whereby the fins of the carriers are completely raised out of the refrigerant and then guided downwardly at 23 into a tank 24 containing relatively warm liquid, which may be refrigerant, at a temperature above the freezing point of the comestible. Adjacent the warm tank is an unloading station 90 25 at which may stand other operators to unload comestibles from the carriers. The operation of the device is so timed that the comestibles will be frozen during the time the carriers pass through the tank of cold refrigerant and the passage of the carriers through the tank of relatively warm liquid will impart just sufficient heat to each carrier so that the comestibles thereon may be loosened without trouble and removed from 100 the carriers.

95 Referring now particularly to Figures 5 and 7 it will be seen that refrigerant is admitted to the tank through the inlets 26, passing through the manifold 27 from which it is discharged through the discharge openings 28. Referring particularly to Figure 5 it will be seen that the manifold is so arranged that the openings 28 are disposed between the fins 19, as these fins pass the manifold. Therefore the refrigerant will be discharged in a direction generally parallel to the length of the carriers and will set up a current between the fins, it being understood that there is a discharge opening between 110 each pair of fins. The carrier is moved towards the right, as viewed in Figure 7, whereas the current of the refrigerant is in the opposite direction, as indicated by the arrows in that figure. In order to insure a 115 continuously fresh supply of cold refrigerant, I employ a plurality of inlets and outlets, having found in this embodiment that good results are obtained by having a pair of inlets and a pair of outlets disposed within 120 125 130

the length of two carriers. The outlets are indicated at 29 in Figure 7 and these outlets communicate with a manifold 30 having a plurality of openings 31 therein through which the refrigerant may pass. This arrangement divides the tank 6 into a plurality of sections, each having inlets and outlets disposed adjacent opposite ends thereof.

Disposed above the bottom 32 of the tank 10 is the false bottom 33 which is shown as a plate supported upon the two manifolds 27 and 30. The refrigerant coming from the discharge openings 28 flows along on top of the false bottom 33 and then downwardly 15 around its other end and into the openings 31 of the outlet manifold. The excess refrigerant will accumulate between the two bottoms and will form a cushion to insulate the refrigerant above the false bottom from the relatively warm air beneath the bottom 32, thus increasing the efficiency of the apparatus. The inlet manifold 27 is so arranged 20 that it will prevent flow of the refrigerant directly from the openings 28 to the openings 31 and this is also prevented by the fact that the refrigerant leaves the openings 28 with sufficient current to flow the length of the false bottom, or until it strikes the next inlet manifold 27, when it will be deflected 25 to the outlets 29.

Referring now particularly to Figures 1, 2, 3 and 4, it will be seen that I have provided a cleaning apparatus designated generally at 34 and comprising a rotary brush 35 operated by a motor 36 in a direction opposite to the movement of the carriers 10, as indicated by the arrows in Figure 4. The brush is preferably received within a housing 37 and the housing is provided at its bottom with scrapers 38 and 39, one on each side of the housing. The scraper 38 will remove from a carrier a large portion of the coarser material which may be stuck thereto. The carrier will then be subjected to the action of the rotating brush, followed by a spray 40, and the scraper 39 will remove the remaining material which has been thoroughly loosened and softened by the brush and spray.

In order to increase the efficiency of operation of the apparatus the cold refrigerant tank is preferably enclosed throughout its length in a shed 41 and in the shed are preferably placed suitable refrigerating coils 42 to maintain the temperature of the air therein at a desirable low point. The coils are not relied upon to freeze the fish or other comestibles on the carriers but to cool the air so that the refrigerant in the tank will not have to perform that function and may be used 60 entirely for freezing the comestibles.

In operation the fish or other comestibles are placed upon the carriers at the loading station 9, as the carriers pass the station. The carriers then enter the shed and the fins 65 on the carriers pass through the circulating

refrigerant, it being remembered that the refrigerant is moving in a direction opposite to that of the carriers. The fins in the refrigerant present a large conducting surface to the refrigerant and they also are of large cross-sectional area so that the heat from the comestibles may be readily conducted to the conducting surface. The conduction is aided by means of the strengthening ribs 43 which not only strengthen the carriers but also provide additional conducting means. As the fins pass through the refrigerant the steps on the fins will prevent the formation of any films of warm refrigerant because of the agitation which they cause, as pointed out above. Because of the arrangement of inlets and outlets a constant supply of cold refrigerant is furnished, and this refrigerant is constantly agitated by the fins, so that the refrigerant warmed by the fins is carried away at once, and replaced by cold refrigerant. Therefore it will be seen that the comestibles are frozen entirely by conduction directly through the carrier to the refrigerant. The large conducting cross-section, together with the large 70 conducting surface makes this possible, and then the heat, when it reaches the refrigerant, is rapidly carried away by the continuously replenished supply of fresh cold refrigerant. When the end of the shed is 75 reached at the point 8 the carriers are automatically lifted from the cold refrigerant and run through the relatively warm liquid to loosen the comestibles thereon, as previously explained.

It will thus be seen that the expense of using a large number of pans for long periods of time is avoided. The fish or other articles may be taken directly from the carriers and packed for shipping or other disposition. If desired, a number of fish or pieces of fish, such as fillets or the like, may be frozen in the form of a block, as shown in Figure 10, by placing them in a container 44 on a carrier to receive the fillets 45 or the like. This container is bottomless, as shown, so that the heat from the food may pass directly to the carrier and thus through the carrier to the refrigerant.

Certain articles which it may be desired to freeze, such, for example, as smoked fillets, do not make good contact with a carrier because they will not lie flat thereon, thus leaving air pockets between the carrier and the comestibles which act as insulation to prevent passage of heat from the comestibles to the carrier. This difficulty is overcome in my invention by providing in the shed 41 a compartment 46 having therein a door 47 opening to the atmosphere. This compartment is 80 preferably disposed at the end of the shed next the loading station 9. The carriers upon which comestibles are to be placed are permitted to pass the loading station and enter the cold refrigerant in the tank within the 85

compartment 46 without any comestibles thereon. By the time one of these carriers reaches the door 47 the surface will have assumed a temperature well below the freezing point so that, when a fillet or the like is placed on the carrier and pressed down thereon, the moist surface of the fillet will stick to the cold surface of the carrier wherever the two are brought together under pressure. Therefore the above arrangement permits the fillets or other comestibles to be placed on the carriers at the door 47 and pressed down on the carriers by hand. The compartment is separated from the rest of the shed so as to prevent entrance of warm air into the main part of the shed and therefore serves the additional purpose of an air lock, preventing the free access of outside air to the shed or tunnel. By this method the contact surface on the comestible immediately freezes and the enlarged surface contact between the comestible and the carrier, which is thus produced, is maintained until the comestible is removed.

From the above it will be apparent that I have provided a novel and improved apparatus which will freeze comestibles in a most efficient manner and much more expeditiously than is possible by prior art methods.

The necessity of providing containers, except for special comestibles such as shown in Figure 10, is avoided and the heat is conducted from the comestibles directly to the refrigerating medium by means of the carriers, which are in direct contact with both the comestibles and the refrigerant and which are provided with large contact surfaces for contact with the comestibles and the refrigerant.

In freezing whole fish by this process some varieties, such as flounder, possess long flat surfaces so that they may be laid on the warm plate at loading station 9 and of their own weight will have such contact with the freezing plate that they will freeze rapidly in the tunnel or shed 41. With other varieties, such as mackerel, the fish are so round that the area of contact between fish and plate would be relatively small if loaded at station 9. To improve the freezing speed of such latter fish they may be placed on freezing plates at the door 47, after such plates have assumed temperatures well below freezing, and pressed by hand in order to enlarge the contact surface. Such enlarged contact surface will be maintained throughout the freezing action because the moist surface of the fish will be in contact with a plate which is cold enough to cause the fish to adhere thereto, while if it were in contact with a warm plate it would not adhere thereto.

The heat is carried from the large contact surface of a comestible to the large conducting surface in the refrigerant by means of conductors of large cross-section. Moreover, the carriers at the same time prevent the re-

frigerant from coming in contact with the comestibles. It will be noted that the top of the tank is preferably disposed below the level of the top of the carrier 10 so that any refrigerant in the tank would overflow before it would reach the top of the carrier. The apron 21 further provides a seal along the outer edge of the tank to prevent the refrigerant from reaching the top surface of the carrier and similar aprons could, if desired, be placed along the other edges of the carriers, for the same purpose. 70

The refrigerant will be continually circulated to carry away the heat which is conducted to it from the fins and the plurality of inlets and outlets insure a continual supply of fresh cold refrigerant. This refrigerant is continually agitated so as to insure that fresh refrigerant is always in contact with the fins and this is achieved by the stepped formation of fins shown in Figure 9. The agitation may be increased by roughening the surfaces of the fins either by providing the corrugations 48 shown in Figure 11 on a fin 19 or the recesses 49 in Figure 12 on a fin 19'. The form of drive employed for the conveyor is preferably one which will permit adjusting the speed of movement of the carriers so that the time which a comestible spends in the shed or tunnel may be varied to insure proper freezing of the comestibles, as some articles of food require a longer time to freeze than do others. 90

The result of the construction described above is a very efficient apparatus which will very greatly cut down the time of freezing comestibles and will perform this result at greatly reduced cost. While I have shown and described one form which my invention may take, this has been done merely for the purposes of illustration, as I am aware that many changes of form and arrangement of parts may be made without departing from the spirit of my invention and, therefore, I do not intend to limit myself except by the appended claims. 105

I claim:

1. A freezing apparatus comprising a carrier, means on said carrier to support comestibles out of contact with the cooling medium during the freezing operation, depending elements on the carrier to conduct heat away from said comestibles, said elements contacting with said cooling medium whereby the heat is removed from the elements. 115

2. A freezing apparatus comprising a carrier, means on said carrier to support comestibles, elements on the carrier to conduct heat away from said comestibles, said elements contacting with a stream of refrigerant 125 whereby the heat is removed therefrom, and means on said elements to agitate said refrigerant.

3. A freezing apparatus comprising a track, a tank having a refrigerant therein, 130

carriers maintaining the comestibles out of contact with the refrigerant during the freezing operation supported on said track and having depending elements contacting with the refrigerant, and means for moving said carriers along said track with said elements in said refrigerant.

4. A freezing apparatus comprising a track, a tank having a refrigerant therein, carriers maintaining the comestibles out of contact with the refrigerant during the freezing operation supported on said track and having depending elements contacting with the refrigerant, said elements having large cross-sections and large conducting surfaces in contact with the refrigerant, and means for moving said carriers along said track with said elements in said refrigerant.

5. A freezing apparatus comprising a track, a tank having a refrigerant therein, carriers supported on said track and having elements contacting with the refrigerant, said elements having large cross-sections and large conducting surfaces in contact with the refrigerant, means for moving said carriers along said track with said elements in said refrigerant, and means on said elements for agitating said refrigerant.

6. A freezing apparatus comprising a track, a tank having a refrigerant therein, carriers maintaining the comestibles out of contact with the refrigerant during the freezing operation supported on said track and having depending elements contacting with the refrigerant, means for moving said carriers along said track with said elements in said refrigerant, and means causing the refrigerant to flow in a direction opposite to the movement of the carriers.

7. A freezing apparatus comprising a tank divided into a plurality of sections, an inlet and an outlet for refrigerant in each section at opposite ends thereof, whereby refrigerant will flow lengthwise of each section, a carrier disposed above said tank and having elements depending into the refrigerant, and means for moving said carrier with said elements in said refrigerant.

8. A freezing apparatus comprising a tank divided into a plurality of sections, a carrier disposed above said tank and having parallel fins depending into said tank, an inlet and an outlet for refrigerant in each section at opposite ends thereof, a manifold communicating with the inlet and discharging refrigerant between said fins, and means for moving said carrier so that said fins will move through said tank.

9. A freezing apparatus comprising a tank divided into a plurality of sections, a carrier disposed above said tank and having parallel fins depending into said tank, an inlet and an outlet for refrigerant in each section at opposite ends thereof, a manifold communicating with the inlet and discharging refriger-

erant between said fins, and means for moving said carrier so that said fins will move through said tank, the movement of the carrier being opposite to the movement of the refrigerant.

10. A freezing apparatus comprising a tank means dividing said tank into upper and lower parts, means for circulating refrigerant through the upper part of said tank, and means maintaining a cushion of relatively non-circulating refrigerant adjacent the bottom of said tank.

11. A freezing apparatus comprising a tank divided into a plurality of sections, an inlet for refrigerant adjacent one end of each section and causing refrigerant to flow toward the other end thereof, a false bottom in said section disposed beneath said inlet and stopping short of the other end of said section, and an outlet disposed beneath said false bottom adjacent said other end of said section.

12. A freezing apparatus comprising a track, two tanks disposed adjacent said track, and a carrier supported on said track and having heat-conducting elements extending into said tanks as the carrier moves along the track, one of said tanks containing relatively cold refrigerant to freeze comestibles on said carrier, and the other tank containing relatively warm liquid to loosen said comestibles from the carrier.

13. A freezing apparatus comprising an endless conveyor, a plurality of carriers for comestibles operated by said conveyor, a loading station and an unloading station disposed adjacent said conveyor, and a tank of refrigerant disposed adjacent said conveyor between said stations, said carriers maintaining the comestibles out of contact with the refrigerant during the freezing operation having heat conducting elements extending into the refrigerant in said tank.

14. A freezing apparatus comprising an endless conveyor, a plurality of carriers for comestibles operated by said conveyor, a loading station and an unloading station disposed adjacent said conveyor, a tank containing cold refrigerant disposed adjacent said conveyor between said stations, said carriers having heat-conducting elements extending into the refrigerant in said tank, and a second tank containing relatively warm liquid adjacent said unloading station to receive said heat conducting elements to warm said carriers and to loosen comestibles thereon.

15. A freezing apparatus comprising an endless conveyor, a plurality of carriers for comestibles operated by said conveyor, a loading station and an unloading station disposed adjacent said conveyor, a tank containing cold refrigerant disposed adjacent said conveyor between said stations, said carriers having heat conducting elements extending

into the refrigerant in said tank, a second tank containing relatively warm liquid adjacent said unloading station to receive said heat-conducting elements to warm said carriers and to loosen combustibles thereon, and means for cleansing said carriers after they pass said unloading station and before they reach said loading station.

16. A freezing apparatus comprising an endless conveyor, a plurality of carriers for combustibles operated by said conveyor, a track supporting said carriers, a loading station and an unloading station disposed adjacent said conveyor, a tank containing relatively cold refrigerant disposed adjacent said conveyor between said stations, a tank containing relatively warm liquid disposed adjacent said unloading station, said carriers having heat-conducting elements adapted to extend into the refrigerant in said tanks, and means on said track to lift said elements from said cold refrigerant tank and dispose them in said warm liquid tank.

17. A freezing apparatus comprising a tank having a refrigerant therein, a carrier movable with respect to the refrigerant in said tank and having elements contacting with said refrigerant during said movement, said elements being of large cross-section and having large conducting surfaces in contact with the refrigerant, and means on said carrier to maintain combustibles out of contact with said refrigerant.

18. A freezing apparatus comprising a tank having a refrigerant therein, a carrier movable with respect to the refrigerant in said tank and having depending elements contacting with said refrigerant during said movement, and means on said carrier to maintain combustibles out of contact with said refrigerant.

19. A freezing apparatus comprising a conveyor, a plurality of carriers for combustibles operated by said conveyor, a loading station and an unloading station disposed adjacent said conveyor, and a tank containing refrigerant disposed adjacent said conveyor between said stations, said carriers having heat-conducting depending elements extending into the refrigerant in said tank.

20. A freezing apparatus comprising a conveyor, a plurality of carriers for combustibles operated by said conveyor, a loading station and an unloading station disposed adjacent said conveyor, a tank containing refrigerant disposed adjacent said conveyor between said stations, said carriers having heat conducting depending elements extending into the refrigerant in said tank, and a shed enclosing said conveyor between said stations.

21. A freezing apparatus comprising a conveyor, a plurality of carriers for combustibles operated by said conveyor, a loading station and an unloading station disposed

adjacent said conveyor, a tank of refrigerant disposed adjacent said conveyor between said stations, said carriers having heat-conducting depending elements extending into the refrigerant in said tank, a shed enclosing said conveyor between said stations, and a compartment in said shed adjacent said loading station and having a door therein whereby combustibles may be placed upon carriers in said compartment after the carriers have become cooled to a temperature below the freezing point of the combustibles.

22. A freezing apparatus comprising a tank having a refrigerant therein and a carrier movable with respect to the refrigerant in said tank and having depending fins extending into said refrigerant.

23. A freezing apparatus comprising a tank having a refrigerant therein and a carrier movable with respect to the refrigerant in said tank and having fins extending into said refrigerant, said fins being provided with roughened surfaces.

24. A freezing apparatus comprising a track, a tank having a refrigerant therein, carriers supported on said track and having elements contacting with the refrigerant, means for moving said carriers along said track with said elements in said refrigerant, and means to provide a constant supply of cold refrigerant and cause it to flow in a direction opposite to the movement of the carrier.

25. A freezing apparatus comprising a tank divided into a plurality of sections, an inlet and an outlet for refrigerant in each section at opposite ends thereof, whereby refrigerant will flow lengthwise of each section, a carrier disposed above said tank and having elements depending into the refrigerant, and means for moving said carrier with said elements in said refrigerant in a direction opposite to the flow of said refrigerant.

26. A freezing apparatus comprising a tank divided into a plurality of sections, a carrier disposed above said tank and having parallel fins depending into said tank, an inlet and an outlet for refrigerant in each section at opposite ends thereof, a manifold communicating with the inlet and discharging refrigerant between said fins, and means for moving said carrier so that said fins will move through said tank in a direction opposite to the flow of said refrigerant.

27. A freezing apparatus comprising a tank containing a refrigerant, a carrier disposed above said tank and having parallel fins depending into said tank, and means to discharge refrigerant between said fins.

28. A freezing apparatus comprising a tank containing a refrigerant, a carrier disposed above said tank and having parallel fins depending into said tank, means for moving said carrier, and means to discharge

refrigerant between said fins and cause it to flow in a direction opposite to the direction of movement of said carrier.

29. A freezing apparatus comprising a tank containing a refrigerant, a carrier, means on said carrier to maintain comestibles out of contact with said refrigerant, said carrier having parallel fins depending in said refrigerant, and means to discharge refrigerant between said fins. 5

30. A freezing apparatus comprising a tank containing a refrigerant, a carrier, means for moving said carrier, means on said carrier to maintain comestibles out of contact with said refrigerant, a plurality of parallel heat-conducting elements on said carrier contacting with said refrigerant, and means to discharge said refrigerant between said elements and cause it to flow in a direction opposite to the movement of said carrier. 15

31. A freezing apparatus comprising a track, two tanks disposed adjacent said track, and a carrier supported on said track and having heat-conducting elements extending into said tanks as the carrier moves along the track, one of said tanks containing relatively cold refrigerant to freeze comestibles on said carrier, and the other tank containing relatively warm liquid to loosen said comestibles from the carrier, and means on said carrier to maintain the comestibles out of contact with said refrigerant and said warming medium. 25

32. A freezing apparatus comprising an endless conveyor, a plurality of carriers for comestibles operated by said conveyor, a loading station and an unloading station disposed adjacent said conveyor, a tank of refrigerant disposed adjacent said conveyor between said stations, said carriers having heat-conducting elements extending into the refrigerant in said tank, and means on said carrier to maintain the comestibles out of contact with said refrigerant. 35

33. A freezing apparatus comprising an endless conveyor, a plurality of carriers for comestibles operated by said conveyor, a loading station and an unloading station disposed adjacent said conveyor, a tank containing cold refrigerant disposed adjacent said conveyor between said stations, said carriers having heat-conducting elements extending into the refrigerant in said tank, and a second tank containing relatively warm liquid adjacent said unloading station and adapted to receive said heat-conducting elements to warm said carriers and to loosen comestibles thereon, and means on said carrier to maintain the comestibles out of contact with said refrigerant and said warming medium. 40

34. A freezing apparatus comprising a conveyor, a plurality of carriers operated by said conveyor, a loading station and an unloading station disposed adjacent said con-

veyor, a tank containing refrigerant disposed adjacent said conveyor between said stations, and means for cleaning said carriers disposed between the unloading and loading stations, said means comprising a scraper. 45

35. A freezing apparatus comprising a conveyor, a plurality of carriers operated by said conveyor, a loading station and an unloading station disposed adjacent said conveyor, a tank containing refrigerant disposed adjacent said conveyor between said stations, and means for cleaning said carriers disposed between the unloading and loading stations, said means comprising a scraper and a rotary brush. 50

36. A freezing apparatus comprising a conveyor, a plurality of carriers operated by said conveyor, a loading station and an unloading station disposed adjacent said conveyor, a tank containing refrigerant disposed adjacent said conveyor between said stations, and means for cleaning said carriers disposed between the unloading and loading stations, said means comprising a scraper, a rotary brush and a spray. 55

In testimony whereof, I have affixed my signature to this specification.

ALEXANDER H. COOKE.
